(57) **CLAIM**

The ornamental design for a butter stick, as shown and described.

DESCRIPTION

FIG. 1 is an illustration of an isometric view of a first embodiment a butter stick;

FIG. 2 is an illustration of a top view of the butter stick of FIG. 1 with the bottom view being a mirror image thereof; FIG. 3 is an illustration of a front view of the butter stick of FIG. 1, with the back view being a mirror image thereof; FIG. 4 is an illustration of a right side view of the butter stick of FIG. 1, with the left side view being a mirror image thereof;

FIG. 5 is an illustration of an isometric view of a second embodiment a butter stick;

FIG. 6 is an illustration of a top view of the butter stick of FIG. 5 with the bottom view being a mirror image thereof; FIG. 7 is an illustration of a front view of the butter stick of FIG. 5 with the back view being a mirror image thereof; and, FIG. 8 is an illustration of a front view of the butter stick of FIG. 5 with the back view being a mirror image thereof. The unshaded areas shown in evenly-dashed broken lines in the drawings illustrate the portions of the butter stick that form no part of the claim. The dot-dash broken lines at the breaks illustrated in the butter stick sidewalls, end walls and top surface define the bounds of the claim, forming no part thereof. Any portion of the article between those breaks forms no part of the claimed design.
